Primary Examiner — Katherine A Holbrow*Assistant Examiner* — Riya Salil Kamat(74) Attorney, Agent, or Firm — Innovent Law P.C.;
Karima F. Gulick(57) CLAIM

The ornamental design for a board game as shown and described.

DESCRIPTION

FIG. 1 is a perspective view of a board game;
 FIG. 2 is a top plan view thereof;
 FIG. 3 is a bottom plan view thereof;
 FIG. 4 is a front side view thereof;
 FIG. 5 is a rear side view thereof;
 FIG. 6 is a left side view thereof; and,
 FIG. 7 is a right side view thereof.
 The broken lines show portions of the board game and environment and form no part of the claimed design.

1 Claim, 5 Drawing Sheets(56)
